UNITED STATES PATENT OFFICE

92,175

DESIGN FOR AN ELASTIC LACE BRAID

Otto Eugene Huber, Reading, Pa., assignor to
Narrow Fabric Company, West Reading, Pa., a
corporation of Pennsylvania

Application September 21, 1933, Serial No. 49,305

Term of patent 14 years

To all whom it may concern:

Be it known that I, OTTO EUGENE HUBER, a citizen of the United States of America, residing at Reading, in the county of Berks and State of Pennsylvania, have invented a new, original, and ornamental Design for an Elastic Lace Braid, of which the following is a specification, reference being had to the accompanying drawing, forming part thereof.

The drawing is an enlarged plan view of an

elastic lace braid embodying my ornamental design. The braid is shown enlarged approximately one and one-half times actual size, but which in the reduction to patent size will show the braid approximately actual size.

I claim:

The ornamental design for an elastic lace braid, as shown and described.

In testimony whereof I affix my signature.

OTTO EUGENE HUBER.
